UNITED STATES PATENT OFFICE.

JOHN NUTRY, OF BROOKLYN, NEW YORK, ASSIGNOR TO THE NUTRY & COOK MANUFACTURING COMPANY, OF BROOKLYN, NEW YORK.

SAFETY DEVICE FOR COIN-RECEPTACLES.

No. 873,678.

Specification of Letters Patent.

Patented Dec. 10, 1907.

Application filed February 27, 1907. Serial No. 3596,68.

To all whom it may concern:

Be it known that I, JOHN NUTRY, a citizen of the United States, residing in Brooklyn, county of Kings, State of New York, have 5 invented a new and useful Safety Device for Coin-Receptacles, of which the following is a specification.

The object of this invention is to prevent the abstraction of coin through the entrance 10 slot of money box, by a simple and efficient device.

In the accompanying drawing forming part of this specification; Figure 1 is a perspective view. Fig. 2 is a cross section, nor- 15 mal. Fig. 3 is a cross section, with coin enter- tering. Fig. 4 is a longitudinal section.

Like figures refer to like parts.

1 is a portion of coin box, 2 is a bent piece of metal having flattened portion 3, and 20 curved members 4, and having perforations into which pins 5 enter, the pins having heads 6. There is a slot 8 in the box and a corresponding slot in piece 2, the metal forced from the box is pressed down through 25 the slot in 2 and bent so as to secure piece 2 to box 1 as shown at 7. The form of piece 2 is such as to cause the pins to cross each other when in normal position and the perforations to allow the pins to move freely 30 and to part when a coin enters at 9 in Fig. 3. The edges 4 of the piece 2 touches the metal of the box so as to prevent the pins from moving out of the perforations.

The action of this device is such that in any position the pins tend to hang, fall, or lie 35 across the entrance slot and prevent the exit of coin.

Having described my invention what I claim and desire to secure by Letters Patent is:

1. In a coin receptacle having a slot for the entrance of coin, a number of headed pins loosely held by the heads in perforations, in proximity to the coin slot, the pins swinging free so that the points tend to cross the coin 45 slot, substantially as shown.

2. In a coin receptacle having a slot for the entrance of coin, an attachment on the inside of the receptacle, the attachment having perforations, headed pins held in the per- 50 forations so that the points of the pins swing freely across the coin entrance and also swing so as to allow a coin to pass into the receptacle, substantially as shown.

3. In a coin receptacle having a slot for 55 the entrance of coin, an attachment secured on the inside of the receptacle, having a slot or opening corresponding with the slot in the receptacle, and connected by bending the metal from the slot in the receptacle inward 60 through the opening in the attachment, substantially as shown.

JOHN NUTRY.
